TELEVISION SYSTEM

Ciro C. Martinelli, Oaklyn, N. J., assignor to Radio Corporation of America, a corporation of Delaware

Application December 31, 1940, Serial No. 372,466

6 Claims. (Cl. 178—7.5)

This invention relates to improvements in television systems and more particularly to an improved method and apparatus for synchronizing a receiving station with a transmitting station.

In television receiving systems of the general type including a cathode ray tube with horizontal and vertical ray deflecting coils, a horizontal deflection system is used for causing a saw-tooth current wave at a desired line scanning frequency to pass through the horizontal ray deflecting coils and a vertical deflection system is used for causing a saw-tooth current wave at the desired framing frequency to pass through the vertical deflecting coils. For the purpose of synchronization, an oscillator is used to generate sharp voltage peaks whose frequency is locked in step with the operating action at the transmitting station by the transmission of synchronizing impulses which are caused to control the frequency of the oscillation circuit. Heretofore it has been customary to use such an oscillator for producing saw-tooth wave current in the horizontal ray deflecting coils and another similar oscillator for producing a saw-tooth wave current to pass through the vertical deflection coils.

In the design of television receivers, it is desirable to incorporate both horizontal and vertical deflection oscillators within one envelope in order to reduce the number of tubes required. Normally there is enough plate-to-plate coupling within closely adjacent discharge devices to affect adversely the interlacing of the scanning.

According to this invention a single tube providing two discharge paths is utilized to generate both the horizontal and vertical deflection signal and furthermore a circuit is provided whereby coupling between the two discharge devices is prevented.

The primary object of this invention is to provide an improved cathode ray deflection system.

Another object of this invention is to include both the horizontal and vertical oscillator control paths in one envelope.

Still another object of this invention is to reduce the inter-electrode coupling effect of two closely adjacent oscillator circuits.

Other and incidental objects of the invention will be apparent to those skilled in the art from the following specification considered in connection with the accompanying drawing, in which the single figure of the drawing is a combination block and circuit diagram showing a preferred form of this invention.

Referring more particularly to the drawing, block 1 represents a television receiver, amplifier and detector which is adapted to receive a television signal including a video signal and synchronizing pulses. A portion of the output signal from the receiver and the amplifier and detector 1 is applied to a video amplifier 3 which amplifies the picture signals of the composite television signals and applies them to the control electrode 5 of the picture tube 7.

The picture tube 7 includes an electron gun comprising a heater element 9, a cathode element 11, a first anode 13, and a second anode 15 for producing an electron beam which is adapted to scan a screen 16 at the opposite end of the picture tube 7 from the electron gun.

A portion of the signal from the receiver 1 is applied to a synchronizing signal clipper circuit shown by block 17 of the type, for example, which is described in Tolson U. S. Patent No. 2,207,839, issued July 16, 1940, to Radio Corporation of America.

The output signal from the synchronizing signal clipper is passed through a vertical synchronizing pulse filter circuit and channel 19 to the control electrode 21 in the left section of the tube 23 through series resistor 25 and series condensers 27 and 29.

The left section of the tube 23 also includes 30 a cathode 31 and an anode 33. The anode 33 is supplied with a fixed positive potential and is bypassed to ground by a bypass condenser 35.

An inductance 37 has a terminal intermediate its two ends connected to the cathode 31. One end of the inductance is connected to the junction between the series condensers 27 and 29 and the other end of the inductance is connected through a potentiometer 39 to ground. Potentiometer 39 and condenser 41 form the 40 circuit across which appears a sawtooth wave of voltage. The potentiometer controls the amplitude of voltage applied to the grid of the vertical deflection amplifier 42.

The right section of the tube 23 includes a 45 cathode 43, a control electrode 45, and an anode 47. The coupling between the control electrode 45 and anode 47 is provided by a transformer 49 having a winding 51 connected to the control electrode 45 through coupling condenser 53. The winding 51 is also connected to a horizontal 50 synchronizing pulse filter and channel represented by block 55. The horizontal synchronizing pulse filter circuit receives its signal from the synchronizing signal clipper represented by 55 block 17.

Transformer 49 also contains a winding 57 which is coupled to the winding 51 and connected to the anode 47. This winding 57 is also connected to the horizontal deflection amplifier 58. A saw-tooth voltage appears across resistor 59 and condenser 60.

The variable tap of the potentiometer 39 is connected to the vertical deflecting coils 61 of the picture tube 7. The horizontal deflecting coils 62 are energized through the horizontal deflection signal amplifier 58.

When the receiver 1 is tuned to the desired television signal radio frequency, the video amplifier 3 applies a picture modulated signal to the control electrode 5 of the picture tube 7 to modulate in intensity the electron beam which is generated by the associated electron gun.

A portion of the signal from the receiver 1 is applied to the synchronizing signal clipper 17 which passes only that portion of the composite television signal including the horizontal and vertical synchronizing pulses. The output from the synchronizing pulse clipper 17 is applied to the vertical synchronizing pulse filter circuit 19 which passes those synchronizing pulses which are adapted to synchronize the scanning of the electron beam in a vertical direction. The vertical synchronizing pulses are applied to the control electrode 21 of the left section of the tube 23 to control the frequency of the oscillation of the circuit including the left section of the tube 23. The inductance 37 provides the oscillating circuit with the feedback necessary to sustain oscillations by the 180° out of phase potential built up on the cathode 31 with respect to the control electrode 21.

It will be noticed that the anode 33 is supplied with a constant positive voltage so that it may be considered to have a zero alternating current voltage potential. It is therefore necessary to cause the cathode 31 to vary in potential in accordance with the wave shape and frequency of the voltage which it is desired to produce. The coupling provided by the inductance 37 and its natural frequency is adjusted so that the oscillating circuit would oscillate freely at a frequency slightly below that of the incoming synchronizing pulses and the synchronizing pulses provide a trip effect on the oscillator circuit each time these pulses are allowed to disturb the oscillation circuit.

The resulting voltage produced in the inductance 37 is applied across the potentiometer 39 which contains a variable tap connected and adapted to cause a current to flow through the vertical deflecting coils 61 in such a manner as to cause the electron beam to be deflected at the predetermined scanning frequency.

The horizontal synchronizing pulses from the synchronizing pulse clipper 17 are applied to an oscillator circuit including the right hand section of the tube 23. For the purpose of illustration, the circuit described takes a slightly different form than the circuit for the vertical synchronizing voltage generator. In the case of the horizontal deflection voltage generator the necessary coupling between the control electrode 45 and the anode 47 produce sustained oscillations as provided by the transformer 49 having one of its windings 51 in series with the synchronizing pulse source and the control electrode 45 whereby the oscillator including the right-hand section of the tube 23 is "tripped" in accordance with the frequency of the incoming horizontal synchronizing pulses.

The frequency at which the vertical deflection voltage generator will oscillate without any synchronizing signal may be adjusted by varying the resistance of the variable resistance 63. The frequency at which the horizontal deflection voltage generator will operate may be adjusted by varying the resistor 65 connected between the control electrode 45 and the cathode 43 of the right section of the tube 23 or by changing the resistance of the variable resistance 59 in the anode supply voltage source of the right section of the tube 23.

The image size control may be controlled in a vertical direction by varying the variable tap on resistance 39 which in effect varies the amount of saw-tooth wave current applied to the vertical deflecting coil 61. A similar adjustment is provided for adjusting the image size control in the horizontal direction by the variation of the resistance 59 and the anode voltage supply circuit of the horizontal deflection voltage generator. Any change in the fundamental frequency of the whole horizontal deflection voltage generator caused by the change of the resistor 59 in the adjustment of the size control may be compensated for by causing a corresponding change in the resistance 65.

It will be noticed that the left-hand section of the tube 23 is operated such that its anode is at ground potential and the anode of the right-hand section of the tube 23 is operated with its anode at high alternating current potential. Each oscillator circuit also contains its own electron discharge path so that one tube such as the 6C8G is all that is required to produce both horizontal and vertical deflection voltages and satisfactory interlacing may be obtained because of the fact that the grounding of the anode 33 of the left section of the tube 23 with respect to the alternating current voltage the anode 33 acts as a shield between the left and the right-hand sections of the tube 23 whereby there is no coupling between the two oscillating circuits. The grounding of the anode 33 forms an effective shield between the anode 47 which is varying at an alternating current potential and the control electrode 21 and cathode 31 of the vertical oscillator section of the tube 23. Furthermore, the cathode of the horizontal oscillator or right-hand section of the tube 23 is at ground potential while the cathode of the vertical oscillator or left-hand section of the tube 23 is at a high alternating current potential. This prevents coupling in the cathode leads between the two oscillating circuits. There would otherwise be considerable coupling between the cathode leads which come out of the same end of the tube 23. Since the control electrodes of the 6C8-G2 come out at opposite ends of the tube envelope, external coupling between the control electrodes 21 and 45 can easily be eliminated.

While a preferred system for carrying this invention into effect has been indicated and described, it will be apparent to one skilled in the art that this invention is by no means limited to the particular organization shown and described but that many modifications may be made without departing from the scope of this invention as set forth in the appended claims.

I claim as my invention:

1. In a television system including an electron ray scanning device, the combination of an envelope having means therein to develop a plurality of separate electron discharge paths, each of

said means containing a cathode, an anode and a control electrode, and adapted to control the scanning of said electron ray in one of two directions, and means for applying to the anode associated with one discharge path and the cathode associated with the other discharge path substantially constant voltages whereby coupling between said discharge paths is eliminated.

2. In a television system including an electron ray scanning device, the combination of an envelope having means therein to develop a plurality of separate electron discharge paths, each of said means containing a cathode, an anode and a control electrode, each of said means adapted to control the scanning of said electron ray in one of two directions, means for applying to one of said discharge paths a synchronizing signal representative of a predetermined rate of scanning in one direction, means for applying to the other of said discharge paths a synchronizing signal representative of a predetermined rate of scanning in another direction, and wherein the potential of the anode associated with one of said discharge paths and the cathode associated with the other of said discharge paths is maintained substantially constant.

3. In a television system including an electron ray scanning device, the combination of an envelope having a plurality of means each including a cathode, an anode and a control electrode, to develop separate electron discharge paths each to control the scanning of said electron ray in one of two directions, means for applying to one of said discharge paths a synchronizing signal representative of a predetermined rate of scanning in one direction, means for applying to the other of said discharge paths a synchronizing signal representative of a predetermined rate of

scanning in another direction, and means for maintaining constant the difference in potential between the cathode associated with one of said discharge paths and the anode of another of the said discharge paths.

4. An oscillation generator including an electron discharge device comprising an evacuated envelope containing a plurality of separate electron sources and a plurality of electrodes toward which said electrons from said separate sources are directed in separate paths, and means for maintaining substantially constant the difference in potential between the electron source of one of said paths and the electrode toward which the electrons in another of said paths are directed whereby said separate electron paths are shielded one from another.

5. An oscillation generator including an electron discharge device comprising an evacuated envelope containing a plurality of separate electron sources and a plurality of electrodes toward which said electrons from said separate sources are directed in separate paths, and means for maintaining the electrode associated with one of said electron paths, and the electron source of the other of said electron paths at fixed potentials.

6. In a television system including an electron ray scanning device, a scanning signal generator comprising an envelope having means therein to develop a plurality of separate electron discharge paths, each of said means containing a cathode, and an anode and means for maintaining the potential of the anode associated with one of said discharge paths and the cathode associated with the other of said discharge paths substantially constant.
